UNITED STATES PATENT OFFICE.

HARRY E. HOENIG, OF EAST LIVERPOOL, OHIO.

INSULATOR BRACKET.

Application filed December 5, 1922. Serial No. 605,022.

To all whom it may concern:

Be it known that HARRY E. HOENIG, a citizen of the United States of America, residing at East Liverpool, in the county of 5 Columbiana and State of Ohio, has invented new and useful Improvements in Insulator Brackets, of which the following is a specification.

The object of the invention is to provide 10 a bracket for use in supporting insulators for electrical wiring and installation wherein in all the parts including the screw or screw shank or other fastening means whereby attachment of the bracket to a supporting object may be effected, are assembled at the 15 factory or point of construction and reach the consumer in the assembled form so as to minimize loss incident to misplacement of the parts and economize in the expenditure 20 of time necessary to locate the brackets; and furthermore to provide a bracket for the indicated purpose which may be constructed at a small cost, without resorting to casting or mill work, and under conditions insuring 25 the requisite strength, stability and durability; and with these objects in view the invention consists in a construction and combination of parts of which a preferred embodiment is shown in the accompanying 30 drawings, wherein:—

Figure 1 is a side view partly broken away of a bracket embodying the invention.

Figure 2 is an end view of the same.

Figure 3 is a detail view of a portion of 35 the base.

Figure 4 is a similar view of the wrench plate.

Figures 5 and 6 are detail views in perspective respectively of modified forms of 40 the bracket embodying the same essential principles of construction.

Referring particularly to the form of bracket shown in Figures 1 to 4 inclusive it will be noted that it embodies essentially 45 a base 10 and a stem 11 of which the former carries a threaded shank 12 and the latter a transverse insulator pin 13 for supporting the insulators 14.

The body portion of the bracket is formed 50 of a single blank of strap iron or like metal with a portion of the center of the blank as indicated at 15 arranged to form the bearing portion of the base and with the portions of the blank at the ends of said bearing portion bent upward and arranged

in convergent relation to form the side members 16 of the base while the terminal portions of the blank are arranged in parallelism as indicated at 17 to form the stem and are secured together by a transverse 60 rivet 18.

It is preferable particularly as a means of economy in construction to employ a fastening shank or screw 12 which is constructed separately from the bracket, so 65 that the best skill in screw construction may be utilized therein without especial reference to bracket or other features of the bracket in connection with which such screw may be used, and to this end a commercial lag screw or cap screw is employed in this connection and the bearing portion of the base of the bracket is provided with an opening 19 through which the shank of 70 the screw extends, the head 12' thereof resting upon the surface of said bearing portion 75 of the base.

It is desirable, however, that the bracket may be applied to the supporting structure 80 in connection with which it is to be used, or in other words that the shank 12 may be screwed into such supporting object by turning the bracket, as distinguished from turning the screw independently of the bracket, and to this end there is employed 85

in connection with the bracket a wrench plate 20 seated on the bottom or bearing portion of the base between the up-turned convergent portions thereof and provided with a seat 21 of a size and shape adapted to receive the head of the screw and hold it against independent rotation. In the construction illustrated the ends of the wrench plate are interlocked with the base by providing the same with terminal extensions 90

95 22 engaging openings or cut-away portions 23 at the junction of the bearing portion of the base with the upwardly convergent side members thereof, as clearly shown in Figure 1. It is also desirable to hold the fastening screw against displacement or disengagement of its head from the seat 21, and therefore, as shown in the drawing 100

there is employed a retainer 24 secured to and preferably forming a reinforcement of 105 the shank elements 17 of the main blank and depending into such terminal relation to the head of the fastening screw as to prevent its removal from the seat. Deflection of the free portion of said retainer, 110

however, by the exercise of a sufficient amount of force will permit of replacing a broken or damaged screw.

The fastening screw thus being held 5 against longitudinal and rotary movement with relation to the base of the bracket may be screwed into the supporting object to which the bracket is to be attached by turning the bracket with relation to said 10 support and force may be applied to the bracket in carrying out this object either by inserting a rod or similar object forming a lever through the base or by applying a jaw wrench to the base owing to the 15 fact that the strap iron or like metal forming the bracket inclusive of the retainer and wrench plate are of uniform width so that the side edges thereof are flush and form wrench jaw seats to which the jaws of a 20 wrench of the monkey wrench type may be applied to afford the desired leverage.

In the construction illustrated in Figure 25 the base consists of a flat bearing member 25 representing one end of the blank of 30 strap metal and extended in only one direction to form the side member 26 of the base and the shank 27 which is provided with an opening 28 for the reception of the equivalent of the insulator pin 13 shown 35 in Figures 1 and 2. The bearing member of the base shown in Figure 5 is provided with an opening 29 for the shank of the screw 30 while the head of said screw as indicated at 31 is fitted in an opening in 40 the wrench plate 32 corresponding with the wrench plate 20 previously described with the exception that one terminal thereof is upturned to form an ear 33 secured by a rivet 34 in the side member of the base.

Also a retainer 35 is employed in this 45 connection secured in place by the rivet 34 and extending over the screw head to prevent displacement thereof from the seat in the wrench plate.

In the modification illustrated in Figure 50 6 the body portion of the bracket consists of a single blank of strap metal folded to form the base 36 similar in general contour with that shown in Figure 5 and the shank 37 perforated for the reception of an insulator pin and reinforced by a retainer plate 38 similar to that shown in Figure 1 and held in place by a rivet 39 for securing the head 40 of the fastening screw

41 in the seat 42 formed in the wrench 55 plate 43 which as in the construction illustrated in Figure 5 is upturned at one end to form an ear 44 secured to the side of the base by a rivet 45.

Owing to the fact that the elements of 60 the bracket inclusive of the lag screw with the weight of strap metal of commercial or stock dimensions may be formed merely by bending and perforating, it is obvious forming and assembling of the same may be 65 accomplished with facility and at a small cost while the completed article affords a substantial support for the insulator buttons of which the adjacent ends bear against the flat side surfaces of the shank. 70

Having described the invention, what is claimed as new and useful is:—

1. An insulator bracket having a base and stem consisting of a folded blank of 75 strap metal, the base being perforated for the shank of a lag screw, and a wrench plate secured to the base and having a seat for the head of said screw.

2. An insulator bracket having a base and a stem consisting of a folded blank of 80 strap metal, the base being perforated for the shank of a lag screw, and a wrench plate secured to the base and having a seat for the head of said screw, the wrench plate having an interlocking engagement 85 with the base.

3. An insulator bracket having a base and a stem consisting of a folded blank of 90 strap metal and carrying an insulator pin, a lag screw extending through an opening in the base, a wrench plate carried by the base and having a seat for engaging the lag screw head to prevent rotation of the latter, and a retainer for maintaining the lag screw head in seated relation with the 95 wrench plate.

4. An insulator bracket having a base and a stem consisting of a folded blank of 100 strap metal and provided with means for supporting an insulator pin, the base having lag screw engaging means independent of the stem to preclude relative turning movement of the base and screw, and a retainer disposed in the path of axial movement of the screw. 105

In testimony whereof he affixes his signature.

HARRY E. HOENIG.
